T. Flinn,

Prince.

No. 96,411.

Patented Nov. 2, 1889.

United States Patent Office.

THOMAS FLINN, OF BIRMINGHAM, MICHIGAN.

Letters Patent No. 96,411, dated November 2, 1869.

IMPROVEMENT IN SELF-SUPPORTING FENCE.

The Schedule referred to in these Letters Patent and making part of the same

To all whom it may concern:

Be it known that I, THOMAS FLINN, of Birmingham, in the county of Oakland, and the State of Michigan, have invented a new and useful Improvement in Portable Fences; and I do hereby declare that the following is a full and exact description thereof, reference being had to the accompanying drawings, and to the letters of reference marked thereon.

Figure 1 represents a perspective view of a section of a fence, as I propose to construct it;

Figure 2 is a portion of the cap, showing the angular lap-joint;

Figure 3 is a vertical section, on line π π of fig. 4;

Figure 4 is a front elevation; and

Figure 5 is a bottom view of the posts, showing their tenons and the position of the shoulders with reference to each other.

The same letters indicate the same parts in the several figures.

My invention relates to portable fences, which are constructed in sections; and

My improvement consists in the attachment of the posts which support the bars of the fence to the base-plate, by which all nailing is avoided.

A, in the drawings, represents a base-plate of a fence, which is to be made of suitable dimensions, so as to give a firm support to the upright portions of the fence. A mortise is to be cut in the centre of the plate for the reception of the tenons of the posts, to be of the same width as the tenons, its length being such, that when the posts have been inserted, a space is left at one end for the reception of a key.

B B' represent the double posts of a fence, between which the bars are confined. Tenons are to be formed

at their lower ends, fitting into the mortises in their base-plate, to which they are secured by the wedge *b* and key *b'*. The position of the posts with reference to each other is such, that the shoulder formed on the post B stands on the base in line with the mortise, while the shoulder on the post B' stands on it at a right angle to the same.

C represent the bars, the ends of which, in each section of fence, are to be formed as shown in fig. 4, so as to make a lap-joint with the adjoining section. They are to be secured between the double posts in any convenient manner.

D represents the cap, to which the top ends of the posts are firmly secured. The formation of the ends where the sections join is clearly shown in fig. 2.

By the above-described construction and arrangement of the parts, a fence is produced which may be readily taken apart and transported from one place to another, and which, when properly put up, combines strength and a neat appearance.

Having thus described my invention,

What I claim, and desire to secure by Letters Patent, is—

The combination of the base A, posts B, keys *b*, bars C, and cap D, all constructed and arranged substantially as shown and described.

In testimony whereof, I have signed my name to this specification, in the presence of two subscribing witnesses.

THOS. FLINN.
